UNITED STATES PATENT OFFICE.

HARRY C. GEORGE, OF MORRIS TOWNSHIP, MORRIS COUNTY, NEW JERSEY, ASSIGNOR
TO ARROWSMITH MANUFACTURING COMPANY, OF MORRISTOWN, NEW JERSEY, A
CORPORATION OF NEW JERSEY.

ADJUSTABLE INSOLE.

1,418,250.

Specification of Letters Patent. Patented May 30, 1922.

Application filed December 17, 1917. Serial No. 207,422.

To all whom it may concern:

Be it known that I, HARRY C. GEORGE, a citizen of the United States, and a resident of the township of Morris, in the county of Morris, State of New Jersey, have invented certain new and useful Improvements in Adjustable Insoles, of which the following is a specification.

The improvements relate to devices adapted to be placed in boots and shoes and to be used for the purpose of correcting abnormalities of the foot, and particularly to devices of this character which are commonly called insoles.

One of the common defects in the human foot is a tendency of the heel to incline toward one side or the other. The physiological reasons for this need not be discussed, and the effect causing the "wearing down" of the heel of the shoe and in many cases permanent displacement of the calcaneum or os calcis and deformity of the structure of the instep arch is well understood. Most cases of this kind, if taken in the incipient stages or before the abnormal tendency has developed to any considerable extent, may be corrected. The difficulty is that the tendency though recognized is neglected until the deformity has progressed to such an extent as to become painful, at which stage complete correction is often difficult, if not impossible. It has therefore long been recognized by orthopedists and others who have to do with the correction of foot deformities, and by makers of foot wear and correcting devices that a simple contrivance adapted to be adjusted to meet all ordinary cases of the character indicated, which can be bought and adjusted by the user to suit his particular condition, is very desirable. It is the primary object, therefore, of the present improvements to provide a device of this character of simple, inexpensive and serviceable construction, which may be used for the correction of all ordinary cases and applied to either side of either foot by a simple manipulation or adjustment of the parts, and which will in all its adjustments form a secure and effective correcting device. They are illustrated in the accompanying drawings, forming a part hereof, in which an embodiment is shown.

In the said drawings, Figure 1 is a plan of an insole embodying the improvements,

with the parts adjusted to correct a tendency 55 to wear down on the inside of the heel of the right foot; Figure 2 is a similar view of the same device with the parts adjusted to correct the same tendency toward the other side; Figure 3 is a side elevation of the 60 device as illustrated in Fig. 1; Figure 4 is a vertical section on the line 4—4 of Fig. 1, and Figure 5 is a similar section on the line 5—5 of Fig. 2; Figure 6 is a detail of the removable tongue by which the adjustment 65 is made.

The insole consists of two pieces of flexible material A and B, preferably leather, cut to fit the inside of the sole of a shoe and to 70 coincide therewith. These two pieces, forming the insole proper, extend from the heel to the ball of the foot, or a little beyond that point. The design being to have the insole extend from the calcaneum to the anterior 75 metatarsal zone. They are secured together by two rows of stitches C and D extending from the forward part of the insole at the sides to a point near the middle of the heel and forming a V, and are also secured by 80 the marginal stitching E and F crossing the stitches C and D respectively, and extending a short distance beyond them on both sides.

These stitches not only unite the two pieces forming the insole but form pockets 85 for the reception of the tongue G, or any other similar device for adjusting the elevation of the upper surface of the insole. The pockets are indicated by the letters H, I and J, the former being the metatarsal 90 pocket and the two latter the heel pockets.

The tongue G is of peculiar form, on account of which it is adapted to be used for the purpose of correcting the heel deformity in question on either side of either foot. It 95 will be seen that it consists of a heel portion G' and a tongue portion G² extending therefrom, a notch or recess G³ being formed in one edge at the junction of the heel and tongue portions and adapted to receive the 100 point formed by the merger of the rows of stitches C and D. As this recess and the point of the stitches are located centrally the adjusting member G may be reversed and moved from one side to the other as desired, 105 and will coincide with the contour of the insole and be securely held in position in both positions. It is tapered from the back

of the heel portion to the tip of the tongue portion, and from its outer edge toward its inner edge so that in both positions the outer edge of the insole is elevated and the greatest elevation is at the back or extremity of the heel.

The stitches E and H also have a part in the holding of the adjusting piece G inasmuch as the tip of the tongue enters between 10 the rearwardly extending part of these stitches and the stitches C and D, and is held thereby against lateral movement. In this manner when the adjusting piece is placed in position on either side of the insole 15 it is locked by the engagement of the tip of the tongue just described and of the notch G³.

From the foregoing description it will be seen that an insole consisting of an insole 20 proper and an adjusting insert is provided, which may be used to elevate one side of the heel or the other, by simply removing, reversing and reinserting the insert, and that when this is done the parts are held securely 25 in position. The usefulness of the device, however, is limited to insoles sold in pairs or for the right or the left foot, as it will be apparent that one insole with the adjusting device may be used on both feet alternately. This is done by simply reversing 30 the insole and applying it to the opposite foot, in which position it may by the adjustment of the insert G be used to support one side of the heel or the other. This enables the manufacturer to make and the 35 dealer to keep in stock an insole which may be sold singly for either foot or in pairs with a single insert for each insole, which meets all the requirements and is securely 40 locked in all positions.

The forward or metatarsal pocket H may be used to receive any elevating device desired, and it will be apparent that the adjusting device G may be inserted therein 45 to support one side or the other, or that a different device may be employed. To this end short rows of stitches K and L have been provided in the said pocket H, uniting the two pieces A and B, and providing means 50 for holding wedges or other adjusting devices against lateral movement, by having them passed between the said stitches are held by one or the other in manner similar 55 to the engagement of the notch G³ by the point of the stitches C and D.

What I claim is:

1. A device of the character described, comprising an insole proper of flexible material, a piece of material adapted to be 60 applied thereto and to have its major portion lie on one side of the longitudinal axis thereof, and means for holding the said piece of material located in the interior of the insole, said piece of material having a 65 recess engaged by said holding means, said

piece of material being movable to a position in which its major portion lies on the opposite side of said longitudinal axis, and in substantially the same relation to the insole as in the first position, the said holding means being constructed and arranged to hold the said piece of material in both positions. 70

2. The combination of an insole proper constructed to conform approximately to the heel portion of the sole of a shoe, a piece of material adapted to be applied thereto, and to lie in contact with the interior of the insole throughout a portion of the area of the insole, a holding means constructed to 75 limit lateral movement of the said piece, said piece having a recess to receive and engage said means when placed in the insole, said device and recess being located in the interior of the insole and arranged to permit 80 the said piece to be inverted and to occupy a different position with respect to the insole and to also engage said means in the said position. 85

3. The combination of an insole proper 90 constructed to conform approximately to the heel portion of the sole of a shoe, a piece of material adapted to be applied thereto, and to lie in contact with one horizontal surface thereof throughout a portion of the 95 area of the insole, a holding device constructed to limit lateral movement of the said piece, said piece having a recess adapted to receive and engage said device, said device and recess being located centrally of 100 the insole and arranged to permit the said piece to be inverted and to occupy a different position with respect to the insole and to also engage in the said position. 105

4. The combination of an insole proper, 110 comprising a plurality of layers or thicknesses of material, said layers being connected along a line extending from the rear toward the forward part thereof and being disconnected at their rear and a portion of 115 their side edges, an insert piece adapted to be passed into the space between the said layers and to engage the connected portions and to lie on one side of the insole and said insert being reversible to lie on the other side thereof and engage said connected portions. 120

5. In a device such as that set forth in claim 9, said insert piece having a thickened portion on one side constructed and 125 arranged to provide an elevated surface on that side in one position and on the other side when in inverted position.

6. The combination of an insole proper, 130 comprising two layers of material having a line of fastenings extending from a point near one edge to a medial point to the rear thereof, and from said medial point to a point near the opposite edge, said connecting line being in approximately the form

of a V with the point thereof toward the heel of the insole, and a substantially flat piece of material conforming approximately to a portion of one side of the insole adapted to be inserted between the said layers, and to fill the space between the line of connection and the outer edge of said insole, and said piece of material being reversible to occupy the same relative position with respect to the other side.

7. The combination of an insole proper, comprising two layers of material having a line of fastenings extending from a point near one edge to a medial point to the rear thereof, and from said medial point to a point near the opposite edge, and a substantially flat piece of material conforming approximately to a portion of one side of the insole adapted to be inserted between the said layers, and to fill the space between the line of connection and the outer edge of said insole, and said piece of material being reversible to occupy the same relative position with respect to the other side.

8. The combination of an insole proper, comprising two layers of material having a line of fastenings extending from a point near one edge to a medial point to the rear thereof, and from said medial point to a point near the opposite edge, and a substantially flat piece of material conforming approximately to a portion of one side of the insole adapted to be inserted between the said layers, and to fill the space between the line of connection and the outer edge of said insole, and said piece of material being reversible to occupy the same relative position with respect to the other side, said insertable piece having a recess adapted to receive the rearward portion of the connecting line.

9. The combination of an insole proper, comprising two layers of material having

a line of fastenings extending from a point near one edge to a medial point to the rear thereof, and from said medial point to a point near the opposite edge, and a substantially flat piece of material conforming approximately to a portion of one side of the insole adapted to be inserted between the said layers, and to fill the space between the line of connection and the outer edge of said insole, said piece of material being reversible to occupy the same relative position with respect to the other side, and said insole also having a line of fastenings extending along its edges at the extremities of the first named fastening line and forming with the said first named fastening line a pocket for the reception of a portion of said insertable piece.

10. The combination of an insole proper, comprising two layers of material having a line of fastenings extending from a point near one edge to a medial point to the rear thereof, and from said medial point to a point near the opposite edge, and a substantially flat piece of material conforming approximately to a portion of one side of the insole adapted to be inserted between the said layers, and to fill the space between the line of connection and the outer edge of said insole, and said piece of material being reversible to occupy the same relative position with respect to the other side, said insertable piece having a recess adapted to receive the rearward portion of the connecting line, and said insole also having a line of fastenings extending along its edges at the extremities of the first named fastening line and forming with the said first named fastening line a pocket for the reception of a portion of said insertable piece.

Witness my hand this 28th day of November, 1917, at the city of Morristown, in the county of Morris and State of New Jersey.

HARRY C. GEORGE.
